CLAIM

The ornamental design for a kayak with shark features, as shown and described.

DESCRIPTION

FIG. 1 is a top perspective view of a kayak with shark features.

FIG. 2 is a top view of the kayak with shark features of FIG. 1.

FIG. 3 is a bottom view of the kayak with shark features of FIG. 1.

FIG. 4 is a front view of the kayak with shark features of FIG. 1.

FIG. 5 is a back view of the kayak with shark features of FIG. 1.

FIG. 6 is a left side view of the kayak with shark features of FIG. 1; and,

FIG. 7 is a right side view of the kayak with shark features of FIG. 1.

Broken lines in the Figures illustrate portions of the kayak with shark features that form no part of the claimed design.

1 Claim, 6 Drawing Sheets
